UNITED STATES PATENT OFFICE

CHARLES T. CAHILL, OF BOSTON, MASSACHUSETTS

MOLD

Application filed July 25, 1930. Serial No. 470,598.

My present invention relates to molds, and more particularly to a novel and improved mold for use in the manufacture of the novel building unit illustrated, described and claimed in my co-pending application, Serial No. 470,597 filed July 25, 1930.

An important object of the present invention is the provision of a mold having collapsible sides and ends whereby the building unit constructed therein may be easily removed on its completion.

Another object of the invention is the provision of adjustable supporting devices to support the core of said building unit in the mold.

A still further feature of the invention resides in providing said mold with means whereby the mold may be adjusted as the cement or concrete is poured into the mold around the core and form.

Another feature of the invention resides in the provision of novel removable cores, adapted to cooperate with the frame or core of the block to produce desired channels or apertures completely through said block.

Another object of the invention resides in providing said removable cores with pivotal mounted latch members which will form lifting recesses in the blocks during the process of manufacture, but which latches may be readily moved to housed position within the core to permit the removal of said cores from the mold for completion of the building unit.

The above and other objects and features of the invention, combinations of parts, details of construction and advantages, will be hereinafter more fully pointed out, described and claimed.

Referring to the drawing illustrating a preferred embodiment of the present invention,

Fig. 1 is a perspective view of my novel mold in assembled position;

Fig. 2 is a vertical sectional view on the line 2—2 of Fig. 1;

Fig. 3 is a vertical sectional view on the line 3—3 of Fig. 1 with the box-like core and reinforcing members supported in said mold;

Fig. 4 is a perspective view of the removable cores; and

Fig. 5 is a fragmentary cross sectional view on the line 5—5 of Fig. 1.

Referring now to the drawing, for a particular description of the invention, its construction, assembly and operation, 1 designates the base of my novel mold, which is secured to handle members 2 by means of 60 nails 3, or the like, said handle members being supported on cross braces or supports 4, to space the mold from the surface on which it rests.

Sides 5 and 6 are hinged to the base 1 by 65 hinges 7, and the ends 8 are hinged to the base 1 by hinges 9. The sides 5 and 6 carry pins 10 adapted to be engaged by latch members or hooks 11 pivoted to the ends 8 on pins 12. The side 6 is provided with a pair 70 of apertures 13, here illustrated as two in number, although any desired number of these apertures 13 may be provided. Also, while the apertures 13 are illustrated as round, it will be appreciated that the same 75 may be of any desired shape.

Formed on the inner surface of the side 5 is a pair of recesses 14 aligned with the apertures 13 in the side 6. Slidably mounted on the top of the sides 5 and 6 is a pair of cross- 80 arms 15, each of said cross-arms being provided with a depending supporting member 16, preferably formed with a hooked end 17, as clearly illustrated in Fig. 1.

Adapted to be inserted through the apertures 13 are cores 18 having a rounded cross sectional shape, the end 19 of each of said cores being adapted to seat in one of the recesses 14, so that said cores will be supported at each end.

A channel 20 is provided partially through each core 18, and a pivot pin 21 extends transversely through the core, traversing said channel. Pivotally mounted on the pin 21 is a lever 22, one end of said lever being formed as a latch 23 normally projecting above the surface of the core 18. The other end 24 of said lever 22 projects at one side of the handle 25 of said core. A pressure on 10 the projecting end 24 of the lever 22 will, therefore, depress the latch 23 until the same is housed within the core 18.

The novel building unit illustrated, described and claimed in my co-pending application, Serial No. 470,597 has as a part thereof a wooden box-like frame or core 26, to which are affixed metallic straps 27, and fixed in turn to these straps 27 are wire screens or meshes 28. The box 26, of course, 20 may be of a material other than wood, such as fibre, or the like, if desired.

When it is desired to construct my novel building unit, the frame, comprising the box 26, straps 27 and reenforcing meshes 28, is 25 placed within the mold, being supported by the supporting elements 16 which depend from the adjustable supporting members 15. This will space said framework a suitable 30 distance above the bottom 1 of the mold, as well as from the inner surfaces of the sides and ends of the molds. The supporting arms or braces 15 may be slid along the upper edges of the walls 5 and 6 to any predetermined location desired for best support 35 of the building unit frame. When the frame is thus suspended within the mold, the cores 18 are inserted through the apertures 13, and through the passages or channels formed in the box 26 by the walls 29, reenforcing 40 screens or meshes 30 being provided in said channels if desired.

With the mold and frame assembled as in Fig. 3, the latch members 23 will project from the cores 18.

45 The device is now ready for the application of the cement or concrete, which will be poured into the mold, the mold to be agitated by means of the handle members 2 to insure complete filling of the mold by said 50 cement or concrete. Other means or methods to insure complete filling of the mold may be utilized, such as tamping or the like.

When the said concrete has hardened about its frame to the desired condition, the 55 latches 23 will have formed recesses in the completed block to receive lifting hooks or other lifting devices, and may then be withdrawn by pressure on the ends 24 of the levers 22, whereupon the cores 18 may be readily removed from the block. Thereupon the 60 supports 15 and the supporting elements 16 may be removed, the latches 23 released from the pins 10, and the sides and ends of the 65 mold may be collapsed by means of the hinges 7 and 9.

When the block has been removed from the base 1, the mold may be again assembled in condition to receive another frame 26 for subsequent block construction.

I believe that the mold above described 70 is novel, and have, therefore, claimed the same in the present application.

The advantages and merits of my novel mold will be instantly apparent to and understood by those skilled in this art. 75

While I have necessarily described my present invention somewhat in detail, it will be appreciated that I may vary the size, shape, and arrangement of parts within reasonably wide limits without departing from 80 the spirit of the invention.

My invention is further described and defined in the form of claims as follows:

1. A mold of the kind described, comprising a bottom, sides and ends hinged to said bottom, means to hold said sides and ends in closed position, one of said sides having a plurality of apertures therethrough, the other of said sides, on its inner surface, being provided with recesses alined with said apertures, removable cores adapted to be inserted through said apertures and to be supported in said recesses and said apertures, a handle on each of said cores externally of said mold, a latch pivoted in each of said cores adapted to form lifting recesses in a block during the formation of said block in said mold, and means located in said handle to release said latches to permit withdrawal of said cores. 90

2. A mold of the kind described, comprising a bottom, sides and ends hinged to said bottom, means to hold said sides and ends in closed position, one of said sides having a plurality of apertures therethrough, the other of said sides, on its inner surface, being provided with recesses alined with said apertures, removable cores adapted to be inserted through said apertures and to be supported in said recesses and said apertures, a handle on each of said cores externally of said mold, a latch pivoted in each of said cores adapted to form lifting recesses in a block during the formation of said block in said mold, means located in said handle to release said latches to permit withdrawal of said cores, and a plurality of supporting members slidably mounted on the upper edges of said sides. 100

3. A mold of the kind described, comprising a bottom, sides and ends hinged to said bottom, means to hold said sides and ends in closed position, one of said sides having a plurality of apertures therethrough, the other of said sides, on its inner surface, being provided with recesses alined with said apertures, removable cores adapted to be inserted through said apertures and to be supported in said recesses and said apertures, a handle on each of said cores ex- 120

ternally of said mold, a latch pivoted in each of said cores adapted to form lifting recesses in a block during the formation of said block in said mold, means located in said handle to release said latches to permit withdrawal of said cores, a plurality of supporting members slidably mounted on the upper edges of said sides, and a supporting pin associated with each of said supporting members and fixed at one end thereto, and holding means formed on the free end of each of said pins.

In testimony whereof, I have signed my name to this specification.
